UNITED STATES PATENT OFFICE.

FRED D. HOLDSWORTH, OF CLAREMONT, NEW HAMPSHIRE, ASSIGNOR TO SULLIVAN MACHINERY COMPANY, A CORPORATION OF MASSACHUSETTS.

COMPRESSOR-CONTROLLING MECHANISM.

Application filed January 30, 1922, Serial No. 532,681. Renewed July 19, 1928.

My invention relates to compressor controlling mechanisms, and more particularly to automatic means for controlling the running of the compressor and the loading there-
5 of at appropriate times.

An object of my invention is to provide an improved compressor controlling mechanism. Another object of my invention is to provide improved means for controlling the starting and stopping of a compressor in accordance with the demands for compressed air and improved means controlled by the starting and stopping of the compressor for controlling the loading and unloading of the compressor. A further object of my invention is to provide improved electro-pneumatic control means for the loading and unloading of a compressor. Other objects and advantages of my invention will hereinafter 20 more fully appear.

In the accompanying drawings I have shown for purposes of illustration two forms which my invention may assume in practice.

In these drawings,—

25 Fig. 1 is a view mainly in elevation, but partially in section, of a compressor system provided with one illustrative form of my improved controlling means, the electric circuits being shown diagrammatically.

30 Fig. 2 is an enlarged detail view with parts shown in section.

Fig. 3 is a detail of a portion of the electric control means.

35 Fig. 4 is a view similar to Fig. 1, showing a modification.

Fig. 5 is an enlarged detail section through a portion of the latter form of my improved controlling means.

40 Fig. 6 is a section on the line 6—6 of Fig. 4.

In the first illustrative embodiment of my invention, i. e. that which is shown in Figures 1 to 3, inclusive, I have shown the same applied to a compressor 1 having a cylinder 2 in whose bore 3 a piston 4 is adapted to be reciprocated by means of a crank shaft 5 and operative connections (not shown). The compressor discharges by way of a pipe 6 to a receiver 7 through valve mechanism 8 of any suitable form. The admission of air to the compressor cylinder takes place past inlet valves 9 of familiar construction, these valves being normally held closed by springs 10 save when opened by reason of the reduction of pressure within the cylinder bore dur-
ing the suction strokes of the piston. For the purpose of opening the inlet valves and maintaining them open and thereby unloading the compressor when desired, I provide pistons 11 reciprocable in cylinders 12 to 60 which air may be supplied by way of connections 13 under control of mechanism 14 hereinafter more fully described, the passages 13 being connected to the receiver as indicated at 15 through the valve mechanism 14. 65

The compressor is driven by a motor dia-grammatically shown at M, which motor is provided with starting means having a series of resistances 16, 17, 18 and 19, all of which are in circuit when the main switch 20 closes the circuit through the main wires 21 and 22 to the motor. It will be noted that the main switch 20 is controlled by a solenoid 23 which is controlled by a pilot switch 24 whose move-ments are regulated by a diaphragm 25, dia-grammatically shown in Figure 1, the dia-
phragm being responsive directly to receiver pressure by way of a direct connection 26, it being noted that when the receiver pressure is in excess of any predetermined desired 70 amount, the pilot switch 24 will be opened, while when the pressure falls below the de-sired limit, the pilot switch will close and thereby close the main line switch 20. The main line switch has movable therewith a supplemental switch 27 which controls the circuit through a solenoid 28 which serves in turn to close a switch 29 shunting the first resistance 16. The switch 29 carries with it a supplemental switch 30 which closes an op-erating circuit which causes the next succeed-
ing resistance 17 to be shunted and, as each suc-
cessive resistance shunting switch closes, it 75 brings about the completion of a circuit through the means for closing the next re-sistance shunting switch. As devices of this 80 type are now quite well known, no further description of the details is believed nec-
essary save that it may be stated that the move-
ments of each of the resistance shunting 85 switches are controlled by dash pot means as indicated in Figure 3, there being a piston 31 which is traversed by a small opening 32 movable in an oil cylinder 33 whereby the
closing movements of the switches take place 90 relatively slowly, while the opening move-
ments are allowed to take place sharply by
reason of a check valve controlled bypass 95 of a large size 34. An examination of the
connections illustrated will show that open- 100
105
110

ing of the main line switch will cause instantaneous opening of all the resistance shunting switches and, accordingly, that each time that the motor is stopped, it is brought up to speed by the gradual cutting out of the full resistance. It will be observed that by reason of the presence of the dash pot mechanisms described, a sufficient time lapse between the closing of the main switch and the cutting out of all resistance is provided to permit the motor to come up to running speed.

It will be noted that the last resistance shunting switch carries a supplemental switch 35 which closes a circuit through a solenoid 36 and this solenoid controls a lever 37 which operates a plunger 38 and so moves a valve mechanism 39 in the control mechanism 14. The details of this valve mechanism are now well known and, although various other forms might be employed, I have shown herein a mechanism of the type disclosed in the patent to one John L. Osborne, 1,141,975, which mechanism operates upon the depression of the plunger 38 to the position shown in Figure 2 to close a connection from the receiver through the valve mechanism 39 to the connections 13 and operates upon release of the plunger 38 upon interruption of the current supply to the solenoid to supply receiver pressure beneath the plungers 11 and so to unload the compressor. It will be noted from an inspection of Figure 2 that when the solenoid no longer holds the lever 37 in depressed position, the plunger will be raised by reason of the small unbalanced area exposed to pressure thereon, and by a spring 39' forming a part of the mechanism 14, thereby causing the unloading of the compressor.

40 The mode of operation of this form of my invention will now be readily apparent. Let it be assumed that the parts are in the position shown in Figure 1. It will be evident that the inlet valves are being held open and so that the compressor is unloaded. As receiver pressure drops due to air consumption for any purpose, the diaphragm 25 will close the pilot switch 24 and thereby cause closing of the main switch 20 and the starting of the motor. 45 The controller mechanism will then gradually cut out the resistance, bringing the motor up to speed and, when the last resistance is cut out, the switch 35 will close the circuit through the solenoid 36 and so cause the lever 37 to be moved to force down the plunger 38 and by means of the valve mechanism 39 cause loading of the compressor by cutting off the supply of air beneath the plungers 11 and exhausting the cylinders 12. When the receiver 50 pressure again gets too high, the pilot switch will be opened, resulting in the opening of all the resistance shunting switches as well as the main line switch and also resulting in the opening of the circuit through the solenoid 36 whereby the plunger 38 may rise and the

valve mechanism 39 operate to admit pressure beneath the plungers 11 to unload the compressor.

In the form of my invention which I have shown for purposes of illustration in Figures 70 to 6, it will be noted that I have shown a compressor 40 similar to the compressor 1 in every respect save that it does not have inlet valve controlling unloading means, but instead is provided with unloading means of the type shown in Figure 6, it being noted that the discharge line 41 from the compressor 40 communicates with a chamber 42 which is provided with ports 43 and 44 respectively opening to chambers 45 and 46 which in their turn respectively communicate with the atmosphere by means of a line 47, and with the receiver by a line 48. Valves 49 and 50 respectively control the ports 43 and 44, these valves having springs 51 and 52 cooperating respectively with them, the springs 52 being of relatively light strength while the spring 51 is substantially more powerful, serving to hold the valve 49 closed when the compressor is first started up and the receiver is empty, and operating, aided by the fluid pressure admitted into the valve 49, as hereinafter described, to hold the valve 49 closed during the time when the air pressure is below the desired point. It will be noted that the valves 49 and 50 are slidable upon projections 53 and 54 which form housings for the springs 51 and 52 and that the space between the projection 53 and the valve 49 is connected by a pipe 55 to a valve mechanism 56 which controls the communication of the pipe 55 with a connection 57 leading to the receiver. The valve mechanism 56 is identical with that shown in the Osborne patent mentioned in its valve construction, but is provided in addition with a solenoid 58 which is operative when current is supplied thereto to oppose the action of the spring 59. The spring 59 is set so that maximum desired compressor discharge pressure cannot overcome the spring 59, but so that minimum desired compressor discharge pressure aided by the strength of the solenoid 58 can overcome the spring 59 and permit the supply of pressure to the inside of the valve 49 and so maintain the latter seated. It will be noted that a similar pilot switch 24' controlled by a similar diaphragm 25' is provided as in the form of my invention shown in Figure 1 and that the electrical controlling mechanism is identical throughout with that shown in Figure 1 and numbered 16, etc.

From the foregoing description the mode of operation of my second illustrative species will be readily apparent. When receiver pressure is in excess of the predetermined desired amount, the pilot switch 24' will be opened and accordingly no current will be supplied to the motor or to the solenoid 58. Accordingly, the valve mechanism 56 will interrupt the air supply through the line 55

and vent the latter. Thereafter, when the receiver pressure has fallen to the desired minimum and the pilot switch 24' closes, the compressor will be started without load as 5 air compressed by the compressor can be forced out past the valve 49 to the atmospheric vent 47. When, however, the compressor has come up to speed and the last resistance shunting switch has been closed, the 10 solenoid 58 will be energized and with the receiver pressure will overcome the spring 59 and supply pressure past the valve mechanism 56 through the pipe 55 and hold the valve 49 closed. Thereafter, the air compressed 15 by the compressor will flow past the valve 50 and into the receiver.

It will be obvious to one skilled in the art that my improved controlling mechanism can be adapted to use with intake type unloading 20 mechanisms and that if desired various other modifications can be made within the scope of my invention as defined in the appended claims.

While I have in this application specifically described two forms which my invention may assume in practice, it will be understood that these forms of the same are shown for purposes of illustration and that the invention may be modified and embodied 30 in various other forms without departing from its spirit or the scope of the appended claims.

What I claim as new and desire to secure by Letters Patent is:

35 1. In a compressor controlling system, a compressor, electric driving means therefor, pneumatic unloading means for said compressor, controller means for said driving means, and means controlled by said controller means for controlling said unloading means and comprising means constantly biased toward one of its positions by compressor discharge pressure.

40 2. In a compressor controlling system, a compressor, electric driving means therefor, unloading means for said compressor, controller means for said driving means, and means controlled by said controller means for controlling said unloading means including an element constantly pressed longitudinally by compressor discharge pressure, and means controlled by said controller means for controlling said element.

45 3. In a compressor controlling system, a compressor, electric driving means therefor, unloading mechanism for said compressor, controller means for said driving means, means for controlling the operation of said unloading mechanism constantly pressed longitudinally by compressor discharge pressure, means whereby the control of said unloading means is effected by pressure fluid which constantly presses said latter means, and electro-magnetic means controlled by said controller means for governing the re-

sponse of said unloading mechanism controlling means to compressor discharge pressure.

4. In a compressor controlling system, a compressor, electric driving means therefor, unloading mechanism for said compressor, 70 compressor discharge pressure responsive controller means for said driving means, means constantly acted on by compressor discharge pressure tending to move the same in one direction for controlling said unloading 75 mechanism, means whereby the control of said unloading means is effected by a pressure fluid which constantly presses said latter means, and electro-magnetic means controlled by said controller means for controlling 80 said constantly discharge pressure pressed means.

5. In a compressor controlling system, a compressor, electric driving means therefor, unloading mechanism for said compressor, 85 means constantly exposed to longitudinally acting compressor discharge pressure for respectively controlling the operation of said driving means and of said unloading mechanism, and means previously stationary but 90 operative when said driving means controlling means has brought the compressor up to speed to vary the operation of the controlling means for the unloading mechanism.

6. In a compressor controlling system, a 95 compressor, unloading means therefor comprising a controlling element exposed to compressor discharge pressure which tends to move it in one direction, and electro magnetic control means for controlling said unloading means including means also acting upon said element when the compressor reaches full running speed. 100

7. In a compressor controlling system, a compressor, unloading means therefor, and combined electric and discharge pressure controlled pilot means for controlling the operation of said unloading means to effect loading at substantially full running speed. 105

8. In a compressor controlling system, a 110 compressor, unloading means therefor, and combined electric and discharge pressure controlled pilot means for controlling the operation of said unloading means to effect loading at substantially full running speed, 115 said electrical control being governed by the compressor discharge pressure.

9. In a compressor controlling system, a 120 compressor having inlet valves, fluid operated means cooperating with the latter to unload the compressor, an electric driving motor for the compressor, a controller therefor, and means controlled by said controller for controlling said unloading means including a valve mechanism, means associated therewith and subjected to compressor discharge pressure tending to move it in one direction and magnetically actuated means modifying the movement of said valve mechanism. 125

10. The combination with a compressor, of 130

controlling mechanism therefor comprising a pilot valve mechanism operative alternatively to supply fluid compressed by said compressor and to vent the fluid so supplied to effect control of said compressor, said pilot valve mechanism having mechanism whereby it is electro-magnetically controlled and including means for exerting a plurality of different forces to be overcome by said electro-magnetic controlling means, one of said forces being pressure fluid produced and opposing all movement by said electro-magnetic controlling mechanism.

11. The combination with a compressor, of controlling mechanism therefor comprising a pilot valve mechanism operative alternatively to supply fluid compressed by said compressor and to vent the fluid so supplied to effect control of said compressor, said pilot valve mechanism having mechanism whereby it is electro-magnetically controlled and including means for exerting a mechanically and a fluid pressure produced force to be overcome by said electro-magnetic controlling means, the latter force opposing all movement by said electro-magnetic controlling means.

12. The combination with a compressor, of controlling mechanism therefor comprising a pilot valve mechanism operative alternatively to supply fluid compressed by said compressor and to vent the fluid so sup-

plied to effect control of said compressor, and electro-magnetic control means for said pilot valve mechanism, said pilot valve mechanism including a surface exposed to the pressure medium controlled by said pilot valve mechanism for constantly exerting a force opposing movement by said electro-magnetic means and also including spring mechanism having to be overcome by said electro-magnetic means.

13. In a compressor controlling system, a compressor, an electric motor for driving the same, a receiver, a pressure switch adapted upon increase in receiver pressure beyond a predetermined point to stop the motor and upon decrease in receiver pressure below a predetermined point to start the motor, fluid pressure operated unloading means for said compressor, and pilot means for supplying fluid under pressure to said unloading means upon stopping of said compressor, to effect unloading and for venting the fluid previously supplied when the compressor attains substantially full running speed, to load the compressor, said pilot means including a valve opened upon stopping of the motor and closed when the motor has attained full running speed after closing of said pressure switch.

In testimony whereof I affix my signature.

FRED D. HOLDSWORTH.
